United States Patent Office.

MATTHEW CHAPMAN, OF GREENFIELD, MASSACHUSETTS.

Letters Patent No. 70,525, dated November 5, 1867.

IMPROVEMENT IN TABLE CUTLERY.

The Schedule referred to in these Letters Patent and making part of the same.

TO ALL WHOM IT MAY CONCERN:

Be it known that I, MATTHEW CHAPMAN, of Greenfield, in the county of Franklin, and State of Massachusetts, have invented a new and useful Improvement in "Table Cutlery," and that the following description, taken in connection with the accompanying drawings, hereinafter referred to, forms a full and exact specification of the same, wherein I have set forth the nature and principles of my said improvements, by which my invention may be distinguished from all others of a similar class, together with such parts as I claim and desire to have secured to me by Letters Patent.

This invention relates to an improvement in table cutlery, and it consists in forging or swaging knives and forks from one piece of steel, as will be hereinafter more particularly described, whereby a piece of cutlery is produced far surpassing in durability that made in the ordinary manner, and at the same time reducing to a considerable extent the cost of manufacture. In the accompanying plate of drawings my improvement in table cutlery is illustrated—

Figure 1 being a side view of a table-knife made according to the present invention, and

Figure 2 a section through the length of the handle portion to the knife, with the blade in side view,

Similar letters of reference indicate like parts.

In the manufacture of table cutlery, both knives and forks, from steel, as heretofore practised, it has been the custom to forge the blade and tang, with or without a bolster, from one piece, and then fasten the handle to the tang with cement, rivets, or otherwise, but by this construction the fastening of the handle soon loosens and becomes detached. By the present invention this difficulty is avoided.

A, in the accompanying plate of drawings, represents the blade portion to the knife, B the bolster, and C the handle, all constructed or formed out of one solid piece of steel, by forging or swaging, with the same relative proportions each to the other as when manufactured separately, or of different pieces of metal or other material, and attached together as heretofore, the width of the handle and of the knife-blade being in directions, in the present instance, at right angles to each other.

Having thus described my invention, I claim as new, and desire to secure by Letters Patent—

As a new article of manufacture, table cutlery having the blade, bolster, and handle forged or swaged from one solid piece of steel, substantially as herein described.

MATTHEW CHAPMAN.
